[57] CLAIM

The ornamental design for an eyeglass case, as shown and described.

DESCRIPTION

FIG. 1 is a perspective view of an eyeglass case showing my new design, the broken lines shown in FIGS. 1 and 3 being understood to represent conventional stitching;

FIG. 2 is a left side elevational view thereof;

FIG. 3 is a rear elevational view thereof; and,

FIG. 4 is a bottom plan view thereof.
